UNITED STATES PATENT OFFICE.

FRANCIS PAYNE, OF PHILADELPHIA, PENNSYLVANIA, ASSIGNOR TO
MIRIAM L. FRIEDBERGER, OF SAME PLACE.

DESIGN FOR TRIMMING.

SPECIFICATION forming part of Design No. 27,773, dated October 19, 1897.

Application filed April 7, 1897. Serial No. 631,175. Term of patent 7 years.

To all whom it may concern:

Be it known that I, FRANCIS PAYNE, a citizen of the United States, residing at Philadelphia, county of Philadelphia, and State of Pennsylvania, have invented a new and original Design for Trimmings for Fronts of Undervests, Undershirts, Overshirts, and the Like, of which the following is a full, clear, and exact description, reference being had to the accompanying drawing, which forms a part of this specification.

My design relates to trimmings for fronts of undervests, undershirts, overshirts, and the like, and has for its characteristic feature a body composed of the usual relatively heavy wefts and the warps, together with two sets of intersecting relatively fine threads arranged obliquely to the warps and wefts and alternately crossing and looped upon each other, so as to form by themselves a surface of small diamond or square shaped figures alternating with transversely-arranged rows of loops, which, in conjunction with the heavy wefts, present a novel and pleasing appearance to the eye. The body is provided with a suitable and harmonious border.

The design is clearly shown in the accompanying drawing, in which--

A represents the body, and B the border. The base of the body consists of the heavy wefts *a* and the warp-threads *a'*. Upon the top of this surface are the interlaced threads *b*, which are arranged for a short length of the trimming in straight lines obliquely thereupon and intersect each other so as to form by themselves a surface of diamond or square shaped figures, and for another short length of the trimming are looped upon each other so as to form a transverse row of loops. These threads so arranged give upon the surface of the corded base a novel and pleasing effect, which is clearly shown in the drawing.

The border is made up of the looped threads B, interlocking with the contiguous warp-threads *a'* of the body.

Having now fully described my invention, what I claim, and desire to protect by Letters Patent, is--

The design for trimmings, substantially as herein shown and described.

In testimony of which invention I have hereunto set my hand.

FRANCIS PAYNE.
